COMBINATION ELECTRIC DRIVE FOR MOTION PICTURE CAMERAS AND HOLDER THEREFOR

Constantin Paul Lent, New York, N. Y.

Application October 30, 1953, Serial No. 27,399

Term of patent 7 years

(Cl. D61—1)

FIG. 1.

FIG. 2.

FIG. 3.

Fig. 1 is a front perspective view of a combination electric drive for motion picture cameras and holder therefor, showing my new design;

Fig. 2 is a rear elevational view thereof; and

Fig. 3 is a side elevational view thereof taken from the right side of Fig. 2.

The broken line showing of the camera on the drawing is for illustrative purposes only.

What I claim is:

The ornamental design for a combination electric drive for motion picture cameras and holder therefor, as shown and described.
